UNITED STATES PATENT OFFICE.

GEORGE W. SCHROCK, OF KELLOGG, IDAHO.

DRILLING DEVICE.

Application filed October 6, 1923. Serial No. 667,003.

To all whom it may concern:

Be it known that I, GEORGE W. SCHROCK, a citizen of the United States, and a resident of Kellogg, in the county of Shoshone 5 and State of Idaho, have invented certain new and useful Improvements in Drilling Devices, of which the following is a specification.

This invention relates to drilling devices 10 especially adapted for use in oil and gas wells.

Briefly stated an important object of this invention is to provide a drilling mechanism having novel means whereby a limited yieldable connection is provided between the 15 drill bit and the drilling cable so that the strain on the drilling cable is reduced to a minimum when lifting the drill bit.

A further object is to provide a drilling 20 mechanism wherein the cushioning mechanism is interposed in the jars in such a manner that the spring is protected from engagement with any objects or obstructions in the well which would be likely to 25 damage the spring.

A further object is to provide a drilling mechanism of the character specified which is of highly simplified construction, durable in use and cheap to manufacture.

Other objects and advantages will be apparent during the course of the following 30 description.

In the accompanying drawing forming a part of this application and in which like 35 numerals are employed to designate like parts throughout the same,—

Figure 1 is a side elevation of the improved mechanism;

Figure 2 is a side elevation of the mechanism, the view being taken at right angles to Figure 1 and parts being shown in section; and

Figure 3 is a group perspective of the improved mechanism, the parts being disassembled.

In the drawing wherein for the purpose of illustration is shown a preferred embodiment of the invention, the numeral 5 designates a bit attaching member having 50 means of any suitable nature whereby the bit may be attached thereto.

The upper portion of the stem 5 is provided with an attaching pin 6 slidable through the cross member 7 of a jar section 55 8. More specifically the lower portion of the jar section 8 is formed with a rectangular

slot or opening 10 which freely receives the pin 6.

In carrying out the invention the stem 5 is provided at its upper portion and at the lower end of the pin 6 with an enlargement 12 against which the lower end 7 of the jar section 8 may bump so as to cause the bit to engage the rock or other formation with a crushing effect. On the upward movement 60 of the jar section 8 of the end wall 7 engages a coil spring 14 on the pin 6 and compresses the spring. The upper end of the spring is in turn engaged by a nut 16 threaded on the terminal portion of the pin. 70

It will be seen that a yieldable connection is provided between the jar section 8 and the stem 5 so that the drilling cable will not be unduly strained and so that the same will 75 not kink or stretch.

It might be stated that a plurality of attaching sections or joints 20 are joined, as indicated at 21 and 22, and form a means whereby the jar section 8 may be connected to the drilling cable. The lower portions of 80 the several joints 20 are provided with annular enlargements 24 by means of which the gripping members of a fishing tool may be securely engaged with the joints 20 in case a fishing job is necessary. 85

Attention is especially directed to the fact that a U-shaped holding member 30 is provided with a bight portion 32 having a central opening 33 which receives the terminal of the pin 6 and the side members of the 90 U-shaped holding member 30 are arranged on opposite sides of the end wall 7 and are connected to the enlargement 20, as indicated at 14'. The particular function of the U-shaped member 30 is to hold the nut 16 95 in place and to protect the spring 14 from engagement with objects which would be likely to injure the same.

With reference to the foregoing description, taken in connection with the accompanying drawing, it will be seen that the tool may be lifted from engagement with the formation being drilled without undue strain on the drilling cable. As the drilling operation progresses the diameter of the cutter is somewhat decreased and consequently the hole formed thereby greatly decreases in diameter. Therefore, when a newly dressed bit is introduced into the well, the same is likely to stick in the bottom of the hole. 110 For this reason the yieldable connection between the drilling cable and the bit prevents

the drilling cable from being unduly strained and possible breaking.

Having thus described the invention what is claimed is:

- 5 1. A drilling mechanism comprising a jar section having a longitudinal opening and a lower end wall, a drill attaching stem having a pin slidable through the lower end wall of said jar section, a spring confined between the lower end wall of said jar section and the upper end of said pin, and a U-shaped holding member having a bight portion connected to said pin and having side branches arranged exteriorly of said opening and connected to said stem.
- 10 2. A drilling mechanism comprising a jar section having a longitudinal opening and an end wall, a stem having a pin slidable
- 15

through said end wall and having a retaining member, a coil spring confined between 20 said retaining member and said lower end wall of the jar section, a U-shaped holding member having a bight portion connected to said pin and holding said retaining member in position, the sides of said U-shaped holding member being slidably engaged with said lower end wall, the upper portion of said stem being provided with an enlargement arranged in the path of travel of the lower end wall of said jar section, and means 25 connecting the lower terminal portions of said U-shaped holding member with said enlargement, said spring being arranged between and protected by the sides of said U-shaped holding member.

GEORGE W. SCHROCK.
